United States Patent Office

Des. 180,274
Patented May 14, 1957

180,274

BOX FOR A WATCH

Jack Fairchild Fleming, Summit, N. J., assignor, by mesne assignments, to The Bulova Watch Company, Flushing, N. Y., a corporation of New York

Application January 12, 1956, Serial No. 39,707

Term of patent 14 years

(Cl. D80—5)

FIG. 1.

FIG. 2.

FIG. 4.

FIG. 3.

FIG. 5.

Fig. 1 is a perspective view of a box for a watch showing my new design.

Fig. 2 is a top plan view thereof.

Fig. 3 is a front view thereof.

Fig. 4 is a side view thereof.

Fig. 5 is a cross-sectional view taken on line 5—5 of Figure 2.

I claim:

The ornamental design for a box for a watch, as shown.
